(57) **CLAIM**

The ornamental design for a tire as shown and described.

DESCRIPTION

1.1 : Front

1.2 : Enlarged partial view of FIG. **1.1**

1.3 : Left perspective view

1.4 : Enlarged partial view of FIG. **1.3**

1.5 : Left

1.6 : Right perspective view

1.7 : Enlarged partial view of FIG. **1.6**

1.8 : Right

The broken lines in FIG. **1.1**, FIG. **1.3** and FIG. **1.6** are demarcations of the portion of the design visible in the enlarged partial views of FIG. **1.2**, FIG. **1.4** and FIG. **1.7**, and form no part of the claimed design.
